UNITED STATES PATENT OFFICE

2,283,907

HYDRAULIC CIRCULATOR

Philip Berman, New York, N. Y.

Application April 25, 1941, Serial No. 390,258

1 Claim. (Cl. 103—262)

This invention relates to improvements in water circulating devices, and particularly to a circulator which will efficiently utilize the energy of the incoming stream of water under pressure, to cause a rapid circulation of water within the piping of hot water heating installations.

Circulators have heretofore been provided with a water supply nozzle which projected into a mixing chamber having an irregular contour causing sudden changes in stream flow. This arrangement of the device interfered with free flow and produced turbulence and otherwise impaired the efficient operation of the device.

An object of this invention is to provide an improved circulator which avoids the objectionable construction features of the prior art and which comprises a storage chamber which is stream-lined in the direction of flow, and without angles or indentations which cause turbulence and which permits flow therethrough with the least possible resistance.

Another object of this invention is to provide a storage chamber of annular form at least along the entire length of the nozzle, and to make the difference in area of the annular space and the nozzle at the point of inlet to the nozzle greater than the area of the recirculation inlet.

With the above and other objects in view, the invention will be hereinafter more particularly described, and the combination and arrangement of parts will be shown in the accompanying drawing and pointed out in the claim which forms part of this specification.

Reference will now be had to the drawing, 35 wherein like numerals of reference designate corresponding parts throughout the several views, in which:

Figure 1 is a vertical cross-sectional view of the water circulator embodying the invention.

Figure 2 is a cross-sectional view, taken as on line 2—2 in Figure 1.

The water circulator 10 comprises a tubular central portion or body 11. A nozzle 12 has been positioned axially of the said tubular body 11.

A Venturi or compound tube 13 has been threadably secured at the outlet end of the tubular body 11 and in axial alignment therewith. The Venturi tube has a converging lower portion 14, a diverging upper portion 15, a throat 16 and a cylindrical tubular portion 17.

The outlet of the nozzle 12 terminates in considerably spaced relation from the throat 16 of the Venturi tube 13, leaving an annular gap. The nozzle 12 is of conical form so as to increase

the velocity of water passing therethrough. As shown in Figure 1, it will be seen that the outlet edge of the nozzle is substantially of knife-edge thickness which permits merging of the drive and driven streams of water without turbulence.

In operation the water passes through the nozzle 12 and causes the liquid discharged therethrough to be under increased high velocity. The nozzle 12 projects directly into the entrained stream so that the direction of the entrained stream is not changed. The entrained liquid is given an impulse by the circulator jet in the same direction exactly in which it is flowing.

The liquid circulator imparts an impulse effect to the liquid and functions to increase the velocity of the liquid and to create a high suction at the throat of the Venturi tube 13, which suction can entrain and accelerate the circulation.

The outflow from the circulator is in submerged relation centrally of the circulation line, and with the outlined construction of the circulator, the energy in the pressure water supply is fully converted into suction in the circulator.

The circulator 10 has been designed to efficiently utilize the energy of the incoming stream of water which is supplied under pressure to cause a rapid circulation of water within the piping.

Circulators have heretofore been provided with a water supply nozzle which projected into a mixing chamber having an irregular contour. This arrangement of the operating mechanism interfered with the flow and produced turbulence and otherwise interfered with the efficient operation of the device.

This improved circulator avoids the objectionable construction features of the prior art and comprises a mixing chamber which is streamlined in the direction of flow, so that sharp angles or indentations which would cause turbulence are avoided and which permits flow therethrough with the least possible resistance.

The tubular portion 17 forms a metering or mixing chamber in which the driven water meets the drive water from the nozzle. The chamber 17 has an upper metering plane 18 and a lower metering plane 19. I prefer to make the metering junction of these streams take place adjacent the lower metering plane 19. I have found that for maximum efficiency the meeting junction of the drive and driven streams should be positioned at a minimum distance above the lower metering plane of the metering part of

the neck, or mixing chamber. The lower metering plane is positioned above the outlet from the nozzle a distance substantially equal to the outlet diameter of the nozzle.

The body 11 of the water circulator 10 has a recirculation inlet 20 in axial alinement with the nozzle 12. The body 11 has a curved elbow-shaped inlet 21 for drive water.

As shown in the drawings, the body 11 provides a very large storage chamber 22 for recirculating water. The difference in area of the body and the nozzle at the point of inlet to the nozzle being greater than the area of the recirculation inlet, thereby bringing the full discharge head in substantially undiminished degree to the meeting junction, that is, at the point where the conversion of power takes place.

The body portion preceding the nozzle is so curved for easy flow as to overcome nearly all of the loss of elbow friction, by maintaining an expansion in that body until it reaches the nozzle.

In accordance with the patent statutes I have described and illustrated the preferred embodiment of my invention, but it will be understood that various changes and modifications can be made therein without departing from the spirit of the invention as defined by the appended claim.

I claim:

In a stream-lined water circulator, an elongated hollow body for driven water, said hollow body having a curved elbow-shaped inlet terminating in a conical nozzle for drive water under pressure, said hollow body being in circumscribing relation with said nozzle and providing a storage chamber, said body having di-

minished circular cross-sections from said inlet to the discharge end of said nozzle, the inner contour of said body coextensive with said inlet and nozzle being defined by a radius of curvature equal to the maximum inner diameter of said body, said body comprising a cylindrical metering or mixing chamber for said drive and driven water, said mixing chamber having upper and lower metering planes, said lower metering plane being considerably spaced from the outlet from said nozzle a distance substantially equal to the outlet diameter of said nozzle, the inner wall of said body being linearly shaped at its upper end to provide a guide wall substantially parallel with and extending beyond said nozzle for continuously guiding said driven water beyond said nozzle and directly into said mixing chamber, the meeting junction of the drive and driven streams of water being positioned adjacent to said lower metering plane, said mixing chamber communicating with a diverging funnel at the upper end of said body, said hollow body having a recirculation inlet in axial alinement with said nozzle, said storage chamber being of annular form at least along the entire length of said nozzle, the outlet edge of said nozzle being of substantially knife-edge thickness to permit merging of said drive and driven streams of water without turbulence, the difference in area of said body and said nozzle at the point of inlet to said nozzle being greater than the area of said recirculation inlet, thereby bringing the full discharge head in substantially undiminished degree to said meeting junction.

PHILIP BERMAN.
